TRUCK STRUCTURE

Robert B. Cottrell, Chicago, Ill., assignor to American Steel Foundries, Chicago, Ill., a corporation of New Jersey

Application November 4, 1937, Serial No. 172,669

23 Claims. (Cl. 105—197.2)

My invention relates to railway trucks and more particularly to the type generally known as a four wheel railway truck wherein side frames of the truss type are commonly used.

5 In the four wheel railway truck as commonly constructed, the ends of the bolster project through the so-called bolster openings in the spaced side frames and are guided therein by various forms of cooperating guide means between the bolster and the side frames. Because of the definite space limitations that have developed due to the standardization of railway rolling stock, vertical clearance between the 10 spring seat at the bottom of the bolster opening and the compression member at the top thereof has been in practice reduced to a minimum in order to permit a maximum amount of metal in the compression and tension members at the middle portions thereof in the area where the load is applied. These structures are commonly arranged with the bolster openings wide at the bottom and narrow at the top, designed to permit the end of the bolster to be inserted in the wide bottom portion and retained in position in the 15 narrower portion by column guide means when the springs have been inserted under the end of the bolster and positioned on the spring seat of the tension member.

20 Certain operating difficulties arise in connection with trucks of the above described type. Wheel wear requires relatively frequent dismantling of the truck in order to introduce new wheel and axle assemblies. With the above mentioned common type of truck this requires the removal of the spring assembly and lowering of the bolster end before the side frame can be disengaged from the wheel and axle assembly.

25 A further objection to the ordinary truss type of side frame as above described results from the difficulty of meeting the present dimensional and test requirements while at the same time presenting a satisfactory clearance of the bottom of the side frame above the rail. My novel truck arrangement contemplates a side frame structure which will permit an exceptionally high clearance of the bottom of the side frame above the rail.

30 It is an object of my invention to design a four wheel railway truck which will permit a quick wheel change by so arranging the parts of the truck as to permit such a wheel change without removal of the spring assembly from its normal seat on the side frame.

35 A more specific object of my invention is to design a novel type of four wheel truck structure wherein the cooperating parts of the side frame

and bolster structures are so constructed and arranged as to permit the raising of the bolster end, thus disengaging it from the side frame and permitting outward movement of one end of the side frame whereby the associated wheel and 5 axle assembly may be removed and replaced.

A further object of my invention is to design a novel type of truss side frame conforming to present dimensional standards and capable of meeting present test requirements while at the same time devising cooperating means on said side frame for connection to an associated bolster which will permit the dissociation of said bolster from said side frame without dismantling other truck parts including the usual spring assembly. 15

It is a further object of my invention to provide a side frame structure with a novel form of tension member which, in combination with my novel arrangement for connecting the side frame and bolster, will permit exceptionally high rail 20 clearance, a factor much sought after in modern truck design. More specifically, my invention comprehends a tension member having such a novel form between the columns as will permit a relatively shallow structure of the tension mem- 25 ber in that area.

With these and various other objects in view my invention may consist of certain novel features and combinations thereof which will be more apparent from a consideration of the associated drawings and the description thereof as well as the claims. 30

In the drawings—

Figure 1 is a fragmentary side elevation of a four wheel truck structure incorporating my invention; 35

Figure 2 is a plan view thereof; and

Figure 3 is a sectional view through the transverse center line of the side frame shown in conjunction with an end elevation of the bolster and 40 the associated wheel and axle assembly.

Describing in more detail the modification of my invention shown in the drawings, the side frame generally designated 2 has the compression member 4 and the tension member 6 joined intermediate their ends by spaced columns 8, 8, 45 forming therebetween the window opening 10 and merging in the usual manner adjacent their ends in the integrally formed journal box structure 12 forming a means of cooperation with the journal portion 14 of the associated wheel and axle assembly 16. The juncture of the journal box 12 with the tension member 6 is reinforced by the ribs 13. The end portions of the compression and tension members of the side frame 50

are U-shaped in cross section, but the center portion of the compression member above the window opening 10 is substantially L-shaped and the center portion of the tension member below said window opening is a shallow box section with upstanding lateral flanges as most clearly shown in Figure 3. The tension member has the usual centrally located spring seat portion 18 defined by the columns 8, 8 on either side thereof and the outer retaining flange 20 and inner retaining flange 22 within which may be positioned the spring group diagrammatically indicated at 24. This special type of tension member section between the columns, comprising a shallow box section with a widened upper chord having vertical flanges which serve as spring retaining means, permits an exceptionally high rail clearance by virtue of the shallow depth of the said box section below the spring seat portion. In other words, the upstanding flanges on the widened top chord of the shallow box section raise the center of gravity of the tension member in this area to a point which coincides with the said upper chord. Expressed in another way, the neutral axis of this portion of the tension member lies along the upper chord of the shallow box section close to the level of the spring seat.

The windows opening 10 is defined by the vertical flanges 26, 26 inwardly projecting from the columns 8, 8 on the outer face of the frame and by the depending flange 28 along the outer edge of the compression member 4 and by the upstanding flange 20 along the outer edge of the tension member 6. Said flange 28 is reinforced by the centrally located rib 29 and, likewise, the flange 20 is reinforced by the rib 31. Joining the spaced side frames 2, 2 is the bolster 30 of general box-like structure having the usual center bearing 32 for cooperation with the center bearing 40 of an associated car body and side bearings 34, 34. The side walls of the bolster may be provided with openings 36 to permit passage of a brake rod, if required, or as a means of lightening the bolster structure. The bracket 38 may be secured to the side of the bolster as by rivets 40, 40 or integrally formed thereon as a means of brake connection thereto. The ends of the bolster are seated in the usual manner upon the spring group 24 and positioning lugs 41, 41 are provided therefor.

I have arranged a novel form of connection between the guide columns 8, 8 of the side frames and the ends of the bolster. The manner of this cooperation may be most clearly seen in Figure 2 wherein it will be observed that the column guides of the side frame have the centrally located vertical guide flange 42 on either side of which are the cylindrical surfaces 44, 44. The cylindrical surfaces 44, 44 cooperate with complementary surfaces 46, 46 formed on the opposite sides of the bolster end. Between the spaced cylindrical surfaces 46, 46 on the sides of the bolster is formed the channel 48 in form complementary to the guide flange 42 on the associated columns 65 of the side frame.

In the modification illustrated and described herein, I have shown the column guide flanges 42 on the side frame defined by the lateral diagonal plane faces 50 and 52 and the intervening plane face 54 parallel with the transverse center line of the truck. Of complementary form is the channel 48 on the end of the bolster, said channel being defined by the faces indicated respectively at 56, 58 and 60. It may be observed that the faces 56, 58 on the opposite columns of the side

frame lie in a single plane as do also the other faces 52, 52. The two planes defined respectively by the faces 50, 50 and by faces 52, 52 intersect in the vertical plane bisecting the truck transversely. Likewise the faces 56, 56 on the opposite sides of each bolster end define a single plane as do also the faces 58, 58 as indicated by the phantom lines 51 and 53. It will thus be seen that any tendency of the side frames to become out of square with relation to the bolster end results in adequate bearing at each end of the bolster against both of the associated side frame column guide flanges.

It may be observed that the guide flange 42 on each of the columns 8 is located centrally of the column structure, the top of said flange being indicated at 61 (Figure 1) and the bottom thereof at 62. It will also be observed that in my novel side frame structure I have provided along the inner edge of the center portion of the compression member 4 a wide but shallow flange 64, the bottom face of which indicated at 66 is spaced from the top surface 61 of the guide flange 42, a distance indicated at A, sufficient to permit the disengagement of the bolster end from the guide flanges 42 without disturbing other parts of the assembly.

In my novel truck structure it will be observed that the guide ribs 42 are centrally located both vertically and laterally on the side frame columns, 30 thus permitting clearance at the top of the side frame for the application or removal of the bolster as above indicated. A very simple form of guide means is thereby provided and the truck structure as a whole presents an arrangement of maximum simplicity and efficiency.

It is to be understood that I do not wish to be limited by the exact embodiment of the device shown which is merely by way of illustration and not limitation as various and other forms of the device will of course be apparent to those skilled in the art without departing from the spirit of the invention or the scope of the claims.

I claim:

1. In a four wheel truck a truss side frame having a compression member, a tension member, and integral spaced columns forming therewith a central window opening, said compression member having an L-section over said opening with one leg of said L forming a depending flange defining the outer face of said frame, a spring seat on said tension member below said opening, a spring group seated thereon, a bolster having an end projecting into said opening, guide means on each of said columns comprising a cylindrical surface and a vertical flange centrally located on said column both vertically and laterally thereof, said bolster end having a depth less than its vertical clearance from the other leg of said L and having on opposite sides thereof vertical channels cooperating respectively with said flanges and cylindrical faces complementary in form to said surfaces, said parts being so constructed as to permit said bolster to be removed from said opening by elevating said bolster end until said channels may be disengaged from said flanges, whereby a wheel change may be facilitated.

2. In a four wheel railway truck a truss type side frame having a compression member, a tension member, spaced integral columns forming therewith a window opening, each of said members comprising end portions of U-section outwardly of said columns, said tension member having a box section and being widened between said columns and provided with upright inner

and outer flanges forming a spring seat and spring retaining means, said compression member being substantially of L-section between said columns and comprising a depending flange on the outer face of said frame, each of said columns having a centrally located vertical guide flange with diagonal faces and cylindrical faces on opposite sides thereof, and a bolster having an end projecting into said window opening, said bolster end having on opposite sides thereof vertical channels cooperating with said vertical flanges and cylindrical guide faces on opposite sides of each of said channels cooperating respectively with each of the before mentioned faces, said bolster end having a depth less than the vertical distance from the tops of said guide flanges to said compression member.

3. In a railway car truck a truss type side frame having a compression member, a tension member, integrally formed columns forming therewith a window opening, said members having end portions of U-section outwardly of said columns, said compression member having an L-section between said columns with one leg of said L being in the form of the depending flange on the outer face of said frame, said tension member being of box section between said columns and having a widened portion on the upper face thereof with upstanding inner and outer flanges forming a spring seat and spring retaining means, each of said columns having a centrally located vertical guide flange and cylindrical guide faces on opposite sides of said flange, and a bolster having an end projecting into said opening, said end having a depth less than the vertical distance between the top of said guide flange and said compression member and having on opposite sides thereof vertical channels cooperating with said vertical flanges.

4. In a railway car truck a truss type side frame having a compression member, a tension member, integrally formed columns forming therewith a window opening, said members having end portions of U-section outwardly of said columns, said compression member having an L-section between said columns with one leg of said L being in the form of the depending flange on the outer face of said frame, said tension member being of box section between said columns and having a widened portion on the upper face thereof with upstanding inner and outer flanges forming a spring seat and spring retaining means, each of said columns having a centrally located vertical guide flange and cylindrical guide faces on opposite sides of said flange, a bolster having an end of less depth than the vertical distance between the tops of said guide flanges and said compression member projecting into said opening, and vertical channels on opposite sides of said bolster cooperating with said flanges.

5. In a four wheel railway truck a truss side frame having a compression member, a tension member and integral columns forming therewith a bolster opening, said tension member having between said columns a box section of shallow depth the upper chord of which is widened and provided with upstanding flanges, each of said columns having bolster guide means comprising a cylindrical surface and a vertical flange, said flange being centrally located on said column both vertically and laterally thereof, and a bolster end projecting into said opening, the vertical distance between the tops of said flanges and said compression member being at least equal to the depth of said bolster end.

6. In a four wheel railway truck a truss side frame having a compression member, a tension member and integral columns forming a bolster opening, said tension member below said opening having a shallow box section with a widened upper chord having upstanding flanges, each of said columns having bolster guide means centrally located thereon, and a bolster end projecting into said opening and having slot means cooperating with said guide means, the vertical distance between the tops of said guide means and said compression member being at least equal to the depth of said bolster end.

7. In a four wheel railway truck a truss type side frame having a compression member, a tension member, and integral spaced columns forming therewith a bolster opening, said compression member having an L-shaped section over said bolster opening and said tension member having a box section thereunder laterally widened to form a spring seat, a spring group seated thereon, each of said columns having a vertical guide flange centrally located thereon both vertically and laterally thereof, and a bolster having an end extending into said opening engaging said flanges and seated on said spring group, said L section having a vertical leg and a horizontal leg affording vertical clearance for said bolster end, whereby said bolster may be raised beneath said horizontal leg and disengaged from said guide flanges and removed from said opening while said spring group remains in assembly with said side frame.

8. In a railway car truck a truss type side frame having a compression member, a tension member, integrally formed columns forming therewith a window opening, said members having end portions of U-section outwardly of said columns, said compression member having an L-section between said columns with one leg of said L being in the form of the depending flange on the outer face of said frame, said tension member being of box section between said columns and having a widened portion on the upper face thereof with upstanding inner and outer flanges forming a spring seat and spring retaining means, each of said columns having a centrally located vertical guide flange with diagonally arranged faces, and cylindrical guide faces on opposite sides of said flange, the vertical distance between the tops of said guide flanges and the other leg of said L being sufficient to afford clearance for a bolster end of normal depth.

9. In a four wheel railway car truck a truss type side frame having a compression member with a center portion L-shaped in section, a tension member having a center portion of box section, integrally formed spaced columns forming with said members a centrally located window opening, said columns having on their opposed faces vertical guide flanges, said guide flanges being centrally located on said columns both vertically and laterally thereof, and a bolster having an end projecting into said opening, said end having on opposite sides thereof vertical channels cooperating respectively with said vertical flanges, said flanges having vertical clearance from said compression member at least equal to the depth of said bolster end.

10. In a four wheel railway truck a truss type side frame having a compression member, a tension member, and integrally formed spaced columns forming therewith a centrally located bolster opening, said compression member having an L-section over said opening with one leg of

- said L forming a depending flange on the outer face of said frame to afford vertical clearance for an associated bolster end, each of said columns having centrally located guide means comprising spaced cylindrical surfaces and an intervening vertical flange, said vertical flange being centrally located on said column both vertically and laterally thereof, and having vertical clearance with the horizontal leg of said L sufficient to admit a bolster end of normal depth.
11. In a four wheel railway truck a truss type side frame having a compression member, a tension member, and integral spaced columns forming therewith a centrally located bolster opening, said compression member having an L-section over said opening with one leg of said L forming a depending flange on the outer face of said frame, each of said columns having bolster guide means comprising a vertical flange and an adjacent cylindrical surface, said flange being centrally located on said column both vertically and laterally thereof and having sufficient vertical clearance from the other leg of said L to afford space for the reception of a bolster end of normal depth.
12. In a four wheel railway car truck, a truss side frame having a compression member, a tension member and spaced columns forming a bolster opening, said compression member having an L section over said opening with the depending leg of said L defining the outer face of said frame, said tension member under said opening having a relatively flat box section with a widened top chord and upstanding flanges thereon forming a spring seat and spring retaining means, spring means thereon, vertical guide flanges on said columns, and a bolster end extending into said opening and having vertical clearance with said depending leg and slots receiving said guide flanges, said bolster end having a depth less than the vertical distance between the tops of said guide flanges and said compression member whereby said bolster may be disconnected from said side frame without disturbing said spring means.
13. In a railway truck a truss side frame having a compression member, a tension member and spaced columns forming therewith a bolster opening, said compression member having an L section over said opening with the depending leg of said L defining the outer face of said frame, guide flanges centrally located on said columns, and a bolster end extending into said opening, said bolster end having slots for said guide flanges and having a depth less than the vertical distance between said guide flanges and said compression member whereby said bolster end may be inserted in said opening over said flanges and engaged therewith in assembly.
14. In a four wheel railway truck, a truss side frame having a compression member, a tension member and spaced columns forming an opening, vertical guide flanges with diagonal faces centrally located on said columns, and a bolster end extending into said opening, said compression member having an L section over said opening with a depending leg affording vertical clearance for said bolster end, said end having slots complementary in form to said guide flanges for reception thereof and having a depth less than the vertical distance between said guide flanges and said compression member whereby said bolster end may be inserted or removed at the top of said opening.
15. In a four wheel truck a truss side frame having a compression member, a tension member, and integral spaced columns forming therewith a central window opening, said compression member having an L-section over said opening with one leg of said L forming a depending flange defining the outer face of said frame, a spring seat on said tension member below said opening, a spring group seated thereon, a bolster end supported on said spring group and having a depth less than its vertical clearance from the other leg of said L, and guide means on each of said columns comprising a cylindrical surface and a vertical flange centrally located on said column both vertically and laterally thereof, said bolster end having on opposite sides thereof vertical channels cooperating respectively with said flanges and cylindrical faces complementary in form to said surfaces, said vertical clearance permitting said bolster to be raised from said spring group and disengaged from said guide means to permit wheel change.
16. In a four wheel railway truck a truss type side frame having a compression member, a tension member, and integral spaced columns forming therewith a centrally located bolster opening, said compression member having an L-section over said opening with one leg of said L forming a depending flange on the outer face of said frame, a bolster having an end extending into said opening, and having vertical clearance with the other leg of said L at least equal to the depth of said end, and guide means on said columns comprising a vertical flange and spaced cylindrical surfaces, complementary guide means on opposite sides of said bolster end comprising centrally located vertical channels and spaced cylindrical surfaces complementary in form to said first mentioned cylindrical surfaces, said parts being so constructed and arranged as to permit removal of said bolster end from said opening by elevation thereof until said channels on said bolster end are disengaged from said flanges on said columns.
17. In a four wheel railway truck, a side frame having a top member, a bottom member, and columns therebetween forming a window opening, said bottom member below said opening having a shallow box section with a widened upper chord having upstanding flanges, each of said columns having bolster guide means centrally located thereon, and a bolster end projecting into said opening with slot means receiving said guide means, said bolster end having a depth no greater than the vertical distance between the tops of said guide means and said top member.
18. In a railway truck, a side frame having a top member, a bottom member, and integral columns forming a window opening, said bottom member below said opening having a shallow box section with a widened upper chord having upstanding flanges, each of said columns having bolster guide means centrally located therein, and a bolster end projecting into said opening and having channels receiving said guide means, said bolster and said guide means having vertical clearance from said top member at least equal to the depth of said bolster end.
19. In a railway truck, a side frame having a top member, a bottom member, and spaced vertical members forming therewith a window opening, a spring seat on said bottom member beneath said opening, a spring group thereon, said top member having an L-section over said opening with the depending leg thereof defining the outer face of said frame, and the horizontal leg thereof

defining the top of said frame, guide flanges centrally located on said vertical members, and a load carrying member having an end seated on said spring group, said end having vertical channels receiving said guide flanges and having a depth less than the vertical distance between said guide flanges and said horizontal leg, whereby said end may be inserted into said opening over said flanges and engaged therewith in assembly on said spring group.

20. In a railway car truck, a side frame having a top member, a bottom member, and spaced vertical members forming an opening, a spring group on said bottom member in said opening, vertical guide flanges with diagonal faces centrally located on said vertical members, and a load carrying member having an end seated on said spring group in said opening, said top member having an L-section over said opening with a horizontal leg, said end having vertical channels complementary to said guide flanges for reception thereof, said end and said flanges having a vertical clearance from said horizontal leg at least equal to the depth of said end, whereby said end may be inserted in said opening or removed therefrom above said spring group.

21. In a four wheel railway truck, a side frame having a top member, a bottom member, and columns therebetween forming a window opening, said bottom member below said opening having a shallow box section with a widened upper chord having upstanding flanges, each of said columns having bolster guide means centrally located thereon both vertically and laterally thereof, and a bolster end projecting into said opening with

slot means receiving said guide means, the portion of said bolster in abutment with said guide means having a depth no greater than the vertical distance between the tops of said guide means and said top member.

22. In a railway truck, a side frame having a top member, a bottom member, and integral columns forming a window opening, said bottom member below said opening having a shallow box section with a widened upper chord having upstanding flanges, each of said columns having bolster guide means centrally located thereon both vertically and laterally thereof, and a bolster end projecting into said opening and having channels receiving said guide means, said bolster and said guide means having vertical clearance from said top member at least equal to the depth of the portion of said bolster having abutment with said guide means.

23. In a four wheel railway truck, a truss side frame having a compression member, a tension member and integral columns forming a bolster opening, said tension member below said opening having a shallow box section with a widened upper chord having upstanding flanges, each of said columns having bolster guide means centrally located thereon both vertically and laterally thereof, and a bolster end projecting into said opening and having slot means cooperating with said guide means, the vertical distance between the tops of said guide means and said compression member being at least equal to the depth of that portion of said bolster adjacent said guide means.

ROBERT B. COTTRELL. 35
